DESIGN FOR A KNITTED TEXTILE FABRIC

Mitchel E. Hadad, Port Chester, N. Y.

Application December 11, 1939, Serial No. 88,816

Term of patent 3½ years

To all whom it may concern:

Be it known that I, Mitchel E. Hadad, a citizen of the United States, residing at Woodlawn Drive, Byram Ridge, Port Chester, in the county of Westchester and State of New York, have invented a new, original, and ornamental Design for a Knitted Textile Fabric, of which the following is a specification, reference being had to the accompanying drawing forming a part thereof, and in which the figure is a plan view of a section of knitted textile fabric showing my new design.

I claim:

The ornamental design for a knitted textile fabric, as shown.

MITCHEL E. HADAD.
